[57] CLAIM

The ornamental design for a radio pager or similar article, as shown.

DESCRIPTION

FIG. 1 is a top, front and left side perspective view of a radio pager or similar article showing our new design; FIG. 2 is a rear elevational view thereof;

FIG. 3 is a left side elevational view thereof;

FIG. 4 is a bottom plan view thereof; and

FIG. 5 is a top, front and left side perspective view of a second embodiment of the radio pager illustrated in FIG. 1.

FIG. 1

FIG. 2

FIG. 4

FIG. 3

FIG. 5
